UNITED STATES PATENT OFFICE

FREDERIK HARKO DE BRUIN, OF GRONINGEN, NETHERLANDS

DRIVING BELT

Application filed May 16, 1928, Serial No. 278,264, and in the Netherlands December 24, 1926.

This invention relates to driving or transmission belts and particularly to double driving belts preferably made of leather, which are superior to the ordinary double, or layer, 5 driving belts as the same are more flexible and also possess other advantages. The usual double driving belts consist of a lower and upper strap adhesively held together along the entire length. Said belts are very stiff, 10 and their period of usefulness is comparatively short, especially when they run over small pulleys. It has been found, in practice, that with such double belts the lower strap which runs over the pulley becomes torn after 15 a short time. The double belt according to this invention consists of an upper and lower strap, each of the same kind of leather, and the parts which form the upper and lower straps are glued together in the usual manner 20 with a waterproof glue, the upper and lower straps being joined together by means of rust-proof hollow nails or rivets.

The advantages of the belt according to the present invention are the following:—

25 As the upper and lower straps are not adhesively held together, but are riveted together, the double belt retains the flexibility of a single belt and is, therefore, particularly suitable to run over small pulleys. The belt according to this invention may also be used on 30 smaller pulleys, as has hitherto been found practicable with double belts. Owing to its great flexibility, the belt lies much better on the pulley than the usual double belt. The adhesion is considerably greater and about 35 the same as in the case of single belts. Therefore, with a belt according to this invention, greater power can be transmitted than with the usual adhesively held double belts. The belt is, therefore, suitable for any speed permissible on small pulleys. As the belt according to this invention is perforated along its 40 entire length, and the air between the pulley and belt can easily escape through the hollow nails or rivets, the belt will lie properly on the pulley and run smoothly and without jerks. The upper and lower belts are made of similar material. The hollow nails or rivets are introduced through holes punched in 45 the double belt and are turned and pressed

outwardly on the lower edge in such manner that their lower edges lie within the lower surface of the lower strap, a stuffing being provided between the nails or rivets. The lower strap thus rests with leather cushions 55 on the pulley, so that the ends or heads of the nails or rivets do not come in contact with the pulley.

In the drawing, which illustrates one method of carrying the invention into effect:—

60 Figure 1 represents a cross-section through a double belt constructed according to the present invention having a few hollow nails fixed therein.

Figure 2 is a top view of a portion of the 65 belt.

Figure 3 is a perspective view from below of a portion of the belt.

The upper belt 1 is connected with the lower belt 3 by means of hollow nails or rivets 70 2. The lower edge of the nail is turned up or beaded, as shown at 4, and pressed and knocked in such manner that the lower ends of the nails or rivets lie within the lower surface of the lower strap. Cushions or slightly 75 bulged portions 5 are thus formed as shown in Figures 1 and 3.

What I claim is:—

A two-layer driving belt composed of an upper and lower strap each of the same thickness and width and of material having the same tensile strength, the parts of each of the straps are glued together by means of waterproof glue, and a plurality of hollow rivets compressibly securing the two layers 80 firmly together, the ends of said rivets being beaded and countersunk so that the portions of the layers between the rivets are above the ends of the rivets and provide a plurality of pulley-engaging cushions and air escape 85 ports.

In testimony whereof, I affix my signature.

FREDERIK HARKO DE BRUIN.
